UNITED STATES PATENT OFFICE.

IRA WINFRED KYLE, OF MANKATO, KANSAS.

MOLD.

1,108,504.

Specification of Letters Patent. Patented Aug. 25, 1914.

Application filed September 12, 1913. Serial No. 789,543.

To all whom it may concern:

Be it known that I, IRA W. KYLE, a citizen of the United States, residing at Mankato, in the county of Jewel and State of Kansas, have invented new and useful Improvements in Molds, of which the following is a specification.

The invention relates to molds, and more particularly to the class of knock-down forms for making concrete culverts, drains, conduits, or the like.

The primary object of the invention is the provision of a form wherein the top and sides thereof are separable, the top being sectional and having hinges connecting the same so that the parts of the mold can be readily and easily set up for use, and after the hardening of the cementitious material the said form can be easily and quickly removed without damage to the finished product.

Another object of the invention is the provision of a form of this character which is simple in construction, possessing few parts, readily and easily assembled and disassembled as the occasion requires, and also one which is thoroughly reliable and efficient in its purpose and inexpensive in manufacture.

With these and other objects in view, the invention consists in the construction, combination and arrangement of parts as will be hereinafter fully described, illustrated in the accompanying drawing, and pointed out in the claim hereunto appended.

In the drawing:—Figure 1 is a perspective view of a mold or form constructed in accordance with the invention. Fig. 2 is a vertical transverse sectional view through a conduit or culvert showing the mold in position therein. Fig. 3 is a vertical transverse sectional view through the mold. Fig. 4 is a plan view of the top of the mold. Fig. 5 is a similar view, looking toward the opposite side.

Similar reference characters indicate corresponding parts throughout the several views in the drawing.

Referring to the drawing in detail, the form comprises a top A and sides B and C respectively, the top being formed of two sections 5 and 6, which are of similar construction and are connected together through the medium of hinges 7, which are fastened to the outer faces of the sections, while at the outer longitudinal edges of these sections

are secured keepers 8 which project beyond the edges a predetermined distance, the said edges being inwardly beveled as at 9 and likewise the side sections have longitudinal beveled edges 10.

Fixed at intervals to the inner face of the section 5 of the top are transversely disposed straps or bars 11 which are adapted to extend over the section 6 when in alinement with the section 5, while carried by the said section 6 are guide members 12 in which is slidably fitted a locking bar 13, the same being formed at intervals with notches 14 which are adapted to aline with the free ends of the bars 11 so that the same will pass therethrough to lie between the locking bar 13 and the section 6 whereby on the shifting of the bar 13 so that the notches will move out of alinement with the free ends of the bars 11 the section 6 will be locked in the same plane with the section 5. The locking bar 13 at one end is formed with a loop or eye 15 which permits the manipulation thereof for moving it to locking or releasing position. In the assemblage of the top and side sections of the form the same are positioned as shown in Fig. 2 of the drawing, and when the top is in such position the keepers 8 will rest upon the beveled uppermost edges of the side sections B and C so that the cement body can be formed about the form to provide a runway or lead therethrough as shown. After the cementitious material becomes hardened the locking bar 13 is moved to bring the notches into alinement with the free ends of the bars 11, and thereafter the sections can be folded outwardly, thus disengaging the keepers 8 from the uppermost edges of the side sections, and thereafter the side sections are removed from the space formed by the form. It is to be understood that the sides B and C of the mold are held against moving inwardly when said mold is set up by the use of any suitable bracing means.

From the foregoing it is thought that the construction and manner of operation of the device will be clearly understood, and therefore a more extended explanation has been omitted.

What is claimed is:—

A form of the class described comprising a top and side sections separable from each other, the said top being formed in two parts, hinges connecting the two parts of the top to permit the folding thereof, keepers

carried by the two parts of the top and adapted to engage the uppermost edges of the side sections, bars fixed to one part of the top and adapted to overlie the other part 5 when the said parts are in alinement with each other, a locking bar slidably mounted on the other part and adapted to be moved into locking engagement with the first-

named bars for preventing folding of the parts of the top. 10

In testimony whereof I affix my signature in presence of two witnesses.

IRA WINFRED KYLE.
